UNITED STATES PATENT OFFICE

HAROLD EDGAR YARROW, OF SCOTSTOUN, SCOTLAND

WATER TUBE BOILER

Application filed June 11, 1928, Serial No. 284,402, and in Great Britain August 13, 1927.

This invention relates to water tube boilers of the Yarrow type comprising an elevated steam and water drum connected by steam generating tubes with water drums extending parallel with the steam drum along the front and rear of the furnace.

One object of the present invention is to provide means for effectively screening the floor of the boiler casing from excessive radiation from the combustion space. Another object is to provide a capacious combustion chamber having a portion which is substantially rectangular in cross section surmounted by another portion of substantially triangular section as in the ordinary Yarrow type boiler. Another object is to enclose the combustion chamber completely by steam generating water tubes so as to screen effectively the entire casing, sides as well as floor, from excessive heat.

According to the present invention the floor of the boiler casing is screened from excessive radiation by providing a pair of additional water drums which are situated a considerable distance below the ordinary or main water drums of the boiler and extend either parallel therewith or transversely thereto and are connected by water tubes with each other and with either the steam drum or with the main water drums, or with both, thereby forming part of the general water circulation system of the boiler. When it is desired to enclose the combustion space completely, four such additional low level water drums are provided, two arranged parallel with and substantially directly below the main water drums, and two arranged transversely in front and rear respectively of the combustion space, but only one of these pairs of additional water drums need be interconnected by means of water tubes, these interconnected drums being preferably at somewhat different levels to promote circulation of the water.

For convenience it will be assumed in the subsequent description that the boiler has only two main water drums, at each side of the combustion space, but it is to be understood that there may be more than two such main water drums all substantially at the

same level and that the boiler may also be provided with any usual arrangement of steam superheater, re heater, or other heating accessories.

In the accompanying drawings Figs. 1 and 2 are vertical sections in planes at right angles to each other of a Yarrow type boiler embodying the invention; Figs. 3 and 4 are corresponding views of a modified construction; and Fig. 5 is a view corresponding with Figs. 1 and 3 showing a further modification.

As shown in these figures A is the saturated steam and water drum and B', B² the usual or main water drums of a Yarrow boiler connected with the steam drum A respectively by banks C', C² of steam generating tubes. Two additional water drums D', D² are provided parallel with and directly below the water drums B', B² respectively. The drums B', D' are connected by rows of vertical generating tubes F' and the drums B², D² are similarly connected by rows of vertical generating tubes F².

To ensure adequate circulation in the tubes F', F² downcomers H' may be provided between the drums B', D' and similarly downcomers H² between the drums B², D². Alternatively, downcomers J', J² may be arranged to connect the water space of the saturated steam drum A with the lower water drums D', D² as shown in Figs. 3 and 4. Or both sets of downcomers H', H² and J', J² may be provided as shown in Fig. 5.

As shown in Figs. 1 and 2 the lower water drums D', D² are at slightly different levels and in this case the auxiliary transverse drums E', E², arranged respectively at either side of the boiler, are situated parallel with each other at a level intermediate between the lower water drums D', D².

The auxiliary transverse drums E', E² are connected with the water space of the saturated steam drum A by rows of tubes G forming side screens protecting the side walls of the boiler casing from excessive heat, and enclosing the combustion space at the two sides.

The tubes G (or alternatively the tubes F' or F²) are preferably arranged in groups

leaving interspaces L between adjacent groups to accommodate burners suitable for firing the boiler by burning within the combustion space pulverized fuel, oil fuel, blast furnace gas or other suitable form of fuel.

5 The two lower water drums D' , D^2 being at different levels, may be connected by one or more rows of inclined tubes K which form a screen between the combustion space and the floor of the boiler setting.

10 In the modified construction of Figs. 3 and 4 the only material difference is that the lower water drums D' , D^2 are arranged parallel with each other on the same horizontal plane, 15 while the auxiliary transverse drums E' , E^2 are arranged parallel with each other but on different levels, one above and the other below the water drums D' , D^2 . The drums E' , E^2 may be connected by one or more rows 20 of tubes I enclosing the bottom of the combustion space and screening it from the floor of the furnace casing, and as the drums E' , E^2 are at different levels, the gradient of the tubes I ensures the maintenance of the water 25 circulation in the system of water tubes of which they form part. Further, as previously described, the drums D' , D^2 are connected by downcomers J' , J^2 not with the main water drums B' , B^2 but with the water 30 space of the steam drum A . In other respects the two constructions are substantially identical, and the same reference characters are applied to corresponding parts in the several figures.

35 As shown in Figs. 1 and 3 of the drawings the waste gases from the combustion space pass to uptakes on the two sides of the steam drum A , but obviously a baffle may be provided on one side, e. g. between the steam 40 drum A and water drum B^2 , as shown in Fig. 5, so as to constrain the waste gases to pass to a single uptake on one side of the steam drum A . In this case the water drum B^2 on the side away from the uptake would 45 usually be of smaller diameter than the other water drum and have a smaller number of rows in the bank of tubes connecting it with the steam drum A , since the waste gases do not pass completely through the bank of 50 steam generating tubes on their way from the combustion space to the uptake, except in the case of that bank of tubes which is on the uptake side.

55 It will be understood that the transverse drums E' , E^2 and water tubes G may be omitted when it is not desired to enclose the front and rear of the combustion space by water tubes.

60 Adequate circulation in the screening tubes is secured by making each set part of a closed water circuit, and in the case of the floor screen the tubes are given a pronounced inclination to the horizontal.

65 Having thus described the nature of the said invention and the best means I know of

carrying the same into practical effect, I claim:—

1. A Yarrow type water tube boiler comprising a steam drum, two main water drums, one at each side of the combustion space, a pair of additional water drums situated within the boiler setting at a considerable distance below the main water drums, downcomer water tubes and upriser water tubes connecting the said additional pair of water drums with the main water drums, a second additional pair of water drums arranged substantially at right angles to the first-mentioned pair of additional water drums, the individual drums of one of said pairs of additional water drums being at different levels, water tubes connecting the said second pair of additional water drums with the steam drum, and inclined water tubes connecting the individual drums of the pair of additional water drums which are at different levels.

2. A Yarrow type water tube boiler comprising a steam drum, two main water drums, one at each side of the combustion space, a pair of additional water drums situated within the boiler setting at a considerable distance below the main water drums, downcomer water tubes and upriser water tubes connecting the said additional pair of water drums with the main water drums, a second additional pair of water drums arranged substantially at right angles to the first-mentioned pair of additional water drums, water tubes connecting the said second pair of additional water drums with the steam drum, and inclined water tubes connecting the individual drums of the said first pair of additional water drums, said individual drums being at different levels.

In testimony whereof I have signed my name to this specification.

HAROLD EDGAR YARROW.
